UNITED STATES PATENT OFFICE.

GEORGE A. WISE, OF PITTSBURGH, PENNSYLVANIA, ASSIGNOR TO SUTTON-ABRAM-
SEN ENGINEERING COMPANY, OF PITTSBURGH, PENNSYLVANIA, A CORPORATION
OF PENNSYLVANIA.

LEVELING APPARATUS FOR METALLIC SHEETS AND THE LIKE.

Application filed July 20, 1926. Serial No. 123,702.

The invention relates to an improvement in the method of adjusting and manipulating certain of the rolls in sheet and plate flattening machines. The general type machine for which this adjustment is adapted, is the machine shown in the patent to George A. Wise, No. 1,516,627, dated November 25, 1924.

In the above cited patent it will be noticed that all adjustment of rolls is obtained in the upper rolls; the lower rolls being trunnioned in stationary bearings. In the use and operation of the patented machine it has been discovered that if one or two of the lower rolls were tiltable the adjustments would be simpler, and in certain classes of work the tilting of the upper rolls could be dispensed with altogether.

The object of the present invention is to provide means whereby lower rolls of a sheet leveling machine may be adjusted.

In the accompanying drawings Figure 1 is a side elevation of the machine; Figure 2 is a sectional view taken through the machine on the line 2-2 of Fig. 1; Figure 3 is a similar view taken on the line 3-3 of Fig. 1; Figure 4 is an enlarged side elevation of the lower roll adjusting means; Figure 5 is a sectional view on the line 5-5 of Fig. 4; and Figure 6 is a sectional view on the line 6-6 in Fig. 4.

As the new improvement is shown applied to the machine illustrated and described in Patent No. 1,516,627, cited above, and as the operation and adjustment of said machine is unchanged except for the added improvement, it will be unnecessary to describe in great detail any feature except the novel arrangement for tilting one or more of the lower rolls.

The machine comprises a base 1 and side frame members 2, which side members 2 are composed of lower portions 2^a and top pieces 2^b. The upper row of rolls 3 are trunnioned in movable bearings 4, and the manner of controlling said bearings 4 as to move the upper rolls in unison or individually as described in the cited patent. Previously all of the lower rolls 5 were fixed in stationary bearings 6 in the side members 2, but the essence of the present invention resides in having one or more of the lower rolls adjustable relative to the upper rolls 3 which may or may not be in movable journals.

In the drawings two of the lower rolls 7 and 8, are shown adjustable, as this number is found sufficient for most work. Lower portions 2^a of side frames 2 are cored out as shown in Fig. 4, leaving a space or opening 9 for retaining bearings 10 and 11, which trunnion rolls 7 and 8 on the right side of the machine shown in Figures 2 and 3.

In Figure 2 roll 7 is shown mounted in bearings 10 and 10^a. The bottoms of these bearings are rounded so that when the roll 7 is tilted there will always be a line contact to support the bearings in the frame of the machine. As shown, bearing 10 rests on a plate 12 in which threaded shank 13 is fixed by means of pin 12^a. The bevel gear 14 engages the screw 13 and supports said screw in the frame 2^a of the machine. In mesh with gear 14 is bevelled pinion 15 which is solid with shaft 16 and hand wheel 18. Therefore to raise or lower bearing 10 the hand wheel 18 is rotated, which causes gear 14 to revolve on, and raise or lower, fixed screw 13.

Bearings 10 and 11 have a tongue and groove engagement on their adjacent faces at 19 which allows one to slide up or down relative to the other and still maintain their vertical alignment. Bearing plate 12 as shown in section in Fig. 5, has an aperture 20 which allows the passage therethrough of the tongue on bearing 11 in case said plate 12 is raised past the bottom of the bearing. Pins 21 and 22 slidably fix the bearings 10 and 11 in the machine frame 2 and the engagement between the same is similar to the pins 23 in the upper roll bearing 4.

In Figure 3 roll 8 is shown mounted by means exactly similar to those shown in Fig. 2, the only difference being that the tilting of this roll is done from the left side of the machine.

The lower row of rolls is positively actuated by any suitable system of inter-gearing and couplings. Such gears or couplings engage the squared portions 24 which extend from the journal shafts 25 of the several lower rolls.

This machine has all the advantages of the apparatus claimed in the cited patent, and in addition, by having several of the lower rolls tiltable or adjustable, it is easier to prepare the rolls for a new run of sheets which may have a different bend, or dish in them,

or may be of a different size, in any of which cases the rolls must be re-set to properly flex and flatten out said sheets or plates.

It might be desirable to mount both ends 5 of a lower roll on adjustable plates similar to the plate, so that either or both ends of the roll may be vertically adjusted. This feature requires no special illustration, as it involves a mere duplication of the mounting 10 and adjusting elements shown and described.

It has been found that sheets with wavy edges and perfectly flat intermediate portions are the most difficult to straighten. For this reason the apparatus described above is particularly advantageous, as the tilting of one 15 or more of the upper rolls and a corresponding adjustment of one or more of the lower rolls practically confines the flexing of the sheet to any desired area of such sheet.

20 It will be understood that the lower rolls may be adjustable by modified means without departing from the principle or spirit of the invention; the number of tiltable rolls may be varied; and some of the lower rolls 25 may be adjustable with or without tilting the same.

What I claim is:

1. In a machine for leveling sheet and plate metal the combination of a machine 30 frame, a row of upper rolls, a row of lower rolls, rocker bearings at both ends of two lower rolls to permit longitudinal tilting of the rolls, vertically adjustable supporting means at opposite ends of the two tiltable 35 rolls and cooperating with the rocker bearings thereof, and fixed supporting means at the other ends of said rolls.

2. In a machine for leveling sheet and plate metal the combination of a machine 40 frame; a row of upper rolls, a row of lower rolls, rocker bearings at both ends of one of the lower rolls to permit longitudinal tilting of the roll, pins passing through vertical apertures in the bearings, the apertures 45 being of such shape as to permit rocking movement of the bearings relatively to the pins, and vertically adjustable means having a rocking contact with the rocker bearing at one end of the tiltable roll.

3. In a machine for leveling sheet and plate metal the combination of a machine 50 frame, a row of upper rolls, a row of lower rolls, rocker bearings at both ends of a roll of the lower row to permit longitudinal tilt-

ing of the roll, fixed bearings for an adjacent 55 roll of the row having an interlocking engagement with the rocker bearings of the tiltable roll, and vertically adjustable means having a rocking contact with the roller bearing at one end of the tiltable roll.

4. In a machine for leveling sheet and plate metal the combination of a machine 60 frame, a row of upper rolls, a row of lower rolls, rocker bearings at both ends of one of the lower rolls to permit longitudinal tilting 65 of the roll, a plate having a rocking contact with the rocker bearing at one end of the tiltable roll, means arranged to permit vertical movement of the plate but to prevent rotation thereof, an adjusting screw engaged with said plate and held against rotation 70 thereby, and rotatable means arranged to act on said adjusting screw.

5. In a machine for leveling sheet and plate metal the combination of a machine 75 frame, a row of upper rolls, a row of lower rolls, rocker bearings at both ends of two lower rolls to permit longitudinal tilting of the rolls, plates having a rocking contact with the rocker bearings at opposite ends of 80 the two tiltable rolls and each having a rocking contact with the rocker bearing at the end of the roll with which it cooperates, means arranged to permit vertical movement 85 of each of the plates but to prevent rotation thereof, an adjusting screw engaged with each of the plates and held against rotation thereby, and rotatable means arranged to act on said adjusting screws.

6. In a machine for leveling sheet and 90 plate metal the combination of a machine frame, a row of upper rolls, a row of lower rolls, rocker bearings at both ends of a roll of the lower tier to permit longitudinal tilting 95 of the roll, fixed bearings for an adjacent roll of the tier having an interlocking engagement with the rocker bearings of the tiltable roll, a plate having a rocking contact with the rocker bearing at one end of the tiltable roll, means arranged to permit vertical movement of the plate but to prevent rotation 100 thereof, an adjusting screw engaged with said plate and held against rotation thereby, and rotatable means arranged to act on said adjusting screw.

In witness whereof, I hereunto set my hand.

GEORGE A. WISE.
